[57] **CLAIM**

The ornamental design for a mounting stand for a digital input pad, as shown and described.

DESCRIPTION

FIG. 1 is a perspective view of a mounting stand for a digital input pad showing my new design, the broken lines showing of the digital input pad is for illustrative pruposes only and forms no part of the claimed design;

FIG. 2 is a rear elevation view thereof;

FIG. 3 is a front elevation view thereof;

FIG. 4 is a left side elevation view thereof, and being a mirror image view of the right hand side;

FIG. 5 is a top plan view thereof; and,

FIG. 6 is a bottom plan view thereof.
